Filed Oct. 14, 1968, Ser. No. 13,978

Term of patent 14 years

Int. Cl. D25—01

U.S. Cl. D28—1

FIG. 1 is a face elevational view of the bracket shown in FIG. 2 as seen from the side thereof.

FIG. 2 is a side elevational view of the bracket shown in FIG. 1 as seen from the side thereof.

FIG. 3 is an enlarged showing of the top portion of the bracket as seen in FIG. 1 showing detail and taken in the direction of line 3—3 in FIG. 2; and

FIG. 4 is a cross-sectional view of the bracket taken on the line 4—4 of FIG. 3.

The dotted line showing of the fence post, cross-tube, and wire strands are for illustrative purposes only and do not constitute part of my design.

I claim:

The ornamental design for a fence top bracket, as shown and described.
